CHAIR

Henry P. Nordmark, Grand Rapids, Mich., assignor to American Seating Company, Grand Rapids, Mich., a corporation of New Jersey

Application May 3, 1935, Serial No. 19,570

5 Claims. (CL 155—184)

The present invention relates to chairs, particularly such as are used in theatres; and its object is to provide such a chair having an improved back and improved means for mounting the back on its support.

This and any other and more specific objects hereinafter appearing are attained by, and the invention finds preferable embodiment in, the chair construction particularly described in the body of this specification and illustrated by the accompanying drawing, in which:

Figure 1 is a front view of the back of a theatre chair and of a portion of its supporting side standards, partially sectioned on a plane corresponding to line 1—1 of Figure 2;

Figure 2 is a sectional view (enlarged) of a portion of the same taken on line 2—2 of Figure 1;

Figure 3 is a fragmentary view (enlarged) of portions of the chair's back with connecting and mounting means;

Figure 4 is a sectional view thereof taken on line 4—4 of Figure 3;

Figure 5 is a view in perspective of a retaining element;

Figure 6 is a front view of the back of a theatre chair illustrating a modified construction;

Figure 7 is a sectional view (enlarged) of a portion of the same taken on line 7—7 of Figure 6; and

Figure 8 is a view in perspective of the modified retaining element used in the form shown in Figures 6 and 7.

In the drawing is illustrated a theatre chair having a back 1 mounted on supporting side standards 2 as by threaded means passing through the flanges 3 of these standards, a preferable form of such mounting means being shown in Figures 3 and 4.

This chair back comprises a body or frame, the comparatively rigid forward and rearward sheet members 4, 5, of suitable material as "ply wood" or the like, these members being fastened together in the relation shown by suitable means as the screws 6. An upholstery sheet 7 of suitable material, as textile fabric, leather or the like, extends in front of said forward member 4 with stuffing indicated at 8 therebetween. The edge portion 9 of this sheet 7 is turned over the peripheral edge 10 of the forward member 4 and to the position shown wherein it is held or clamped between the frame members 4 and 5.

A rim 11 of metal or the like extends around the peripheral edge 12 of frame member 5 and at 13 is turned over its front side and into held engagement with the lugs 14 of the round flat retaining

elements 15 seated in sockets 16 in the front or inner side of the rearward member 5, these sockets and elements being adjacent the parallel peripheral edges of said members, all as illustrated in Figures 1 and 2, one of said retaining elements being shown in Figure 5.

In the slightly different construction illustrated in Figures 6, 7, and 8, the retaining elements 15¹ are elongated and are fastened, as by screws 17, on the rear or inner side of the forward member 4, with the edge portion 9 of the upholstery sheet 7 held therebetween. Sockets 16¹ in the rearward member 5 may be provided to receive these elements 15¹. In this construction the edge 18 of the rim 11 abuts against the projecting outer end 19 of the elements 15¹. Inasmuch as the edge of the turned over portion 13 of the rim engages under the lugs 14 of the round retaining elements 15 as shown in Figure 2 or under the projecting outer ends 19 of the elongated retaining elements 15¹ as shown in Figure 7, these retaining elements hold the rim on the peripheral edge 12 of the frame member 5 thus dispensing with nails or the like. The rim in either construction is shown with a rear flange 20 engaging the rear side of member 5.

Preferable means shown in Figures 3 and 4 for mounting the chair back on the standards 2 comprises a nut member 21 whose threaded shank 22 extends into a bore 23 through frame member 5 and whose flat head 24 has spurs 25 thrust into the inner or front side of said member. The screw 26 extends through the standard's flange 3 and is turned into this nut member to mount the chair back.

The invention being intended to be pointed out in the claims, is not to be limited to or by details of construction of any embodiment thereof illustrated by the drawing or hereinbefore described.

I claim:

1. In a chair back: comparatively rigid forward and rearward sheet members forming the frame of the back; retaining elements held between said members adjacent the parallel edges thereof having forwardly extending lugs; a rim extending around the edge of the rearward member and turned over the front side thereof into engagement with the inner side of said elements; an upholstery sheet in front of the forward member having its edge portion turned over the edge thereof and between said members; means for fastening said members together with the edge portion of the upholstery sheet clamped between them.

2. In a chair back: comparatively rigid forward and rearward sheet members forming the frame of the back; retaining elements held between said members adjacent the parallel edges thereof having forwardly extending lugs; a rim extending around the edge of the rearward member and turned over the front side thereof into engagement with the inner side of said elements and having a flange engaging the rear side of the rearward member; an upholstery sheet in front of the forward member having its edge portion turned over the edge thereof and between said members; means for fastening said members together with the edge portion of the upholstery sheet clamped between them.
3. In a chair back: comparatively rigid forward and rearward sheet members forming the frame of the back one of said members having sockets in its inner side; retaining elements seated in the sockets having forwardly extending lugs; a rim extending around the edge of the rearward member and turned over the front side thereof into engagement with the inner side of said elements; an upholstery sheet in front of the forward member having its edge portion turned over the edge thereof and between said members; means for fastening said members together with the edge portion of the upholstery sheet clamped between them.
4. In a chair back: comparatively rigid forward and rearward sheet members forming the frame of the back one of said members having
5. In a chair back: comparatively rigid forward and rearward sheet members forming the frame of the back, one of said members having circular sockets adjacent the parallel edges of said members; round flat retaining elements seated in said sockets having forwardly extending lugs; a rim extending around the edge of the rearward member and turned over the front side thereof into engagement with the inner side of said lugs; an upholstery sheet in front of the forward member having its edge portion turned over the edge thereof and between said members; means for fastening said members together with the edge portion of the upholstery sheet clamped between them.

HENRY P. NORDMARK.
